UNITED STATES PATENT OFFICE

167,822

CHILD'S TRICYCLE

Dorr D. Beale, Minneapolis, Minn.

Application March 24, 1951, Serial No. 14,612

Term of patent 14 years

(Cl. D34—15)

To all whom it may concern:

Be it known that I, Dorr D. Beale, a citizen of the United States, residing at Minneapolis, Minnesota, have invented a new, original, and ornamental Design for a Child's Tricycle, of which the following is a specification, reference being had to the accompanying drawing, forming a part hereof.

Fig. 1 is a perspective view of a child's tricycle, showing my new design; and

Fig. 2 is a rear elevational view thereof.

I claim:

The ornamental design for a child's tricycle, substantially as shown.

DORR D. BEALE.
